TIMER FOR CONCRETE MIXERS

Ernest C. Garber and Harold R. McDermott,
Waterloo, Iowa, assignors to Construction Ma-
chinery Company, Waterloo, Iowa

Application January 23, 1933, Serial No. 653,106

15 Claims. (Cl. 83—73)

Our invention relates to improvements in timers and counters for use on rotary batch mixers, and an object of our improvements is to supply for such a mixer, devices in coaction for the above 5 purposes, being simple, inexpensive and effective in use.

Another object of our improvements is to provide in the mechanism means for manually adjusting the timing elements as may be desired, 10 including the provision of a signaling mechanism to announce the completion of mixing of a batch.

Another object of our improvements is to include in the combined mechanisms also a counting means for the batches, and also arranged 15 for operation at the completion of mixing of each batch.

Another object of our improvements is to combine with said devices auxiliary locking means for the tiltable discharge spout of the mixer.

20 All of these objects we have accomplished by the means which are hereinafter described and claimed, and which are illustrated in the accompanying drawings, in which Fig. 1 is a vertical longitudinal section of our invention, with 25 parts broken away. Fig. 2 is a horizontal section thereof also with portions broken away. Fig. 3 is a transverse section thereof, and Fig. 4 is a side elevation of a rotary batch mixer, displaying the association therewith of our improved 30 timer and counter, with the locking device for the discharge spout of the mixer, and with all of these in locked condition, a portion of the mixer skip being broken away.

The side elevation shown in said Fig. 4 is conventional as to the rotary mixer, whose structures are well known in this art. In the mixer 35 a mixing drum with ported heads is shown at 71, and is rotatably mounted in a supporting frame composed of rigidly connected basal beams 51, front and rear corner posts 74 and 52 with top connecting bars 75. Polygonal plates at the rear of the structure at 57 are mounted 40 on the rear posts 52 and top bars 75, and upon the hither bar 75 and front post 74 is secured a 45 laterally projecting bracket 73 upon which is mounted removably the housing 1 for our invention.

The mixer has the usual tiltable skip 56 hinged on pintles 54 through depending fixed arms 55, 50 with the discharge mouth of the skip adapted to deliver materials to be mixed into the rear open flanged receiving port 60 of the drum 71, the pintles 54 also traversing brackets 53 mounted on the rear posts 52. On one hither side wall of 55 the skip 56 is secured a contact plate 56' for a

purpose to be described. On the polygonal plate 57 is rotatably mounted a sheave 58, and a cable 59 is reeved thereover, being connected to the skip and to be moved by means not shown, usually a motor, to lift the skip to its discharging position shown in Fig. 4.

The mixer has also the usual discharge spout 69 whose rear portion extends into the front central port of the drum 71, and this spout may be manually tilted up or down by the usual means shown in Fig. 4. This means includes a transverse rock-shaft having an end crank 65 and mounted in a bracketed bearing 64 secured on a front post 74. On the shaft is fixed a curvate arm 67 which is pivoted at its outer end to a curvate link-bar 68, whose lower end is pivoted at 70 to one side wall of the spout. Upon the crank-shaft mentioned above is also fixed an arm 66.

Referring to Figs. 1 to 3 inclusive, the upper 20 part of the housing 1 has bearing apertures 2 in line longitudinally in its end walls seating slidably the locking bar 6 which has on its hither side face the longitudinally disposed catch 19 with squared rear end and the locking bar has 25 on its opposite side wall to the rear of the catch 19 a laterally disposed pin or spring stop 18 which engages the rear end of a longitudinally disposed coil compression spring 48 seated in a chamber 49 alongside the locking bar. In the 30 rear end of said chamber is placed a shorter coiled compression or cushion spring 50, engageable at times with the adjacent end of the stop 18, to cushion the locking bar at the rear portion of its rearward movement. The rear end of the 35 bar 6 has furcations 5 apertured to receive a pintle bolt 4 and on which the downturned end of a swingable arm 3 is pivoted for vertical swinging, the arm having a head 3' engageable by the plate 56' when the skip 56 is rocking to its discharging position.

The forward end of the locking bar 6 has 40 furcations 20 apertured to receive a pintle bolt 21 on which is pivoted the upper end of a bell-crank lever 22, which at its angle is pivotally 45 mounted on a bracket 61, the other arm of the lever at 62 having an angular projection 63 which may be swung into the path of forward rocking of said fixed arm 66 on the crank-shaft operated manually at its crank 65. In the positions of 50 these parts shown in Fig. 4, the discharge spout 69 is thus locked in its upper or non-discharging position during the rotary mixing operation of the drum 71.

The top of the housing 1 has a medial upright 55

boss 11 upon which may be mounted a signal bell 13 on a screw 14, the bell being sounded by a clapper 9, headed, and whose stem seats slidably in a hole in the housing top to project downwardly into the housing and into a recess with arcuate bottom contactingly in the top of the said locking bar 6. Below said recess another recess 8 is provided in the bottom of the bar for a purpose to be disclosed.

10 The numeral 24 denotes a locking bar latch having its upper end entering a squared socket 12 in the boss 11, and the lower part of this latch bar is seated in a like squared socket in an erect boss 23 within the housing on its bottom floor, said socket also opening on one side. 37 is a single coil spring having one end secured to one side wall of the housing and with its other end bent to enter a hole in the lower part of the said latch 24.

20 26 is a clutch bar having an upwardly directed oblique aperture 25 traversed by the latch bar 24 loosely, and diagonally opposite rear and forward upper and lower angles of the bar may at times bite upon the abutting faces of the latch bar, when the clutch bar is swung downwardly only by means to be described.

In the rear end of the clutch bar 26 a threaded aperture is traversed by a screw 28 whose upper end contacts with the under face of a rigid housing bracket 29, for the purpose of adjustably varying the swinging play of the clutch bar.

30 The numeral 32 denotes a link-bar depending swingingly from a pivotal connection 27 to the forward end of the clutch bar 26 and having its lower end pivotally mounted on a crank-pin 33 on a head 34 secured on the diminished end part 36 of a rock shaft 39 mounted in oppositely directed bearing bosses 35 and 38 on the lower part of the farther side wall of the housing 1. A coiled tension spring 31 connects the lower end part 40 of the link-bar 32 to a depending projection 30 on the forward end of the clutch bar 26 to keep the link-bar away from its dead center. As shown in Figs. 1 and 3 without the housing 1 a sleeve 40 is fixed on the projecting part of the rock-shaft 39, and carries a lever arm 41 on whose rear end is mounted a tread wheel 42 rotatably between stop rings.

45 Referring now to said Fig. 3, the numeral 47 denotes a horizontally projecting stop on the lower end of the locking bar latch 24. At the hither side of the housing a threaded standard 44 has its upper end seated in the bracket part 29 and its lower end in the bottom of the housing. A circular nut 45 is seated on the standard 44 and may be adjustably shifted up or down therewith and held in an adjusted position by a set-screw 46 in the path of upward movement of the stop lug 47 of the latch 24.

50 60 In Fig. 1 is shown within the housing 1 a counting device 18 on whose rotary shaft 17 is a crank 16 pivoted to a headless pin 15 whose upper end extends into the said arcuate socket 8 in the bottom of the locking bar 6.

65 65 As before stated, Fig. 4 shows the mechanisms in their locked positions. When the skip 56 is lowered, the head 3' of the swinging arm 3 is released from the edge of the stop plate 56' after following it for a distance under compulsion of the spring 48, as the spring reacts against the stop pin 10. As the bar 6 moves rearwardly its stop pin engages and is cushioned by the short spring 50. Also the bell crank lever 22 and 62 is swung to lift the engaging finger 63 to cause it to leave the 70 path of movement forwardly of the fixed arm 66

on the crank-shaft, and at the proper time the crank 65 may be rocked over to cause its connections to swing downwardly the spout 69 to a discharging position.

75 However, Figs. 1 to 3 show the relative positions of the parts of the device at the moment when the locking bar 6 is at the limit of its forward stroke, compressing the spring 48, and its catch just disengaged from above the upper end of the latch bar 24, so that the latter has moved up past the abutting end of the catch 19 to its uppermost position, where the resilience of the spring 48 keeps the end of the catch in holding contact with the latch bar, the latter being also held up by the reaction of the lower coiled spring 37. The 10 crank shaft in front being locked, the operator starts the drum 11 in rotation, and the arcuate boss 12 on the drum passes contactingly under and swings up the tread-wheel 42 and lever arm 41, the latter rocking the shaft 39 and the crank-pin 33 by means of the link-bar 32 swinging downwardly the clutch bar 26, the opposite angular edges of the wall of the aperture 25 engaging the latch 24 and moving downwardly the latch bar while compressing the spring 37. The latch 24 20 passes by the frictionally contacting end of the catch 19 slidingly during this operation, but when the arm 41 is swung downwardly after passing over the boss 12, the clutch bar 26 is thereby swung upwardly, the latch 24 then being released by the 25 angular jaws of the clutch bar, but the frictional contact of the catch with the latch remains sufficient to retain the latch in its lowered position without being returned by the spring 37. Before 30 starting the drum in rotation however, the operator adjusts the nut 45 at a desired height on the standard 44, so that the downward travel of the latch bar 24 is adjusted for the timing required.

35 When the latch bar arrives at its lowermost position, its upper end clears the abutting end of the catch 19, releasing the locking bar 6, the spring 48 suddenly reacting to shift the bar 6 back but cushioned by the spring 50. When the locking bar starts back both of the stems of the clapper 9 and push-rod 15 are driven out of the recesses 7 and 8 respectively, the former ringing the bell 13, while the other causes the actuation of the counter 18 to count one more batch mixed. The returning locking bar at this time rocks the lever 22 to release the arm 63, so that the crank 50 shaft may be used to shift the spout 69 to discharge the batch.

45 Various modifications in the details of construction and arrangement of parts of the apparatus and its connections may be made without 55 departure from the principle and scope of the invention as defined in the following claims.

Having described our invention, what we claim as new, and desire to secure by Letters Patent, is:

1. In a mechanism of the character described, 60 a resiliently controlled reciprocating bar having a side lug, a reciprocating standard, resiliently controlled, mounted alongside said bar to cross the path of the lug in a direction at a right angle to the bar, a rock-arm having relatively staggered 65 jaws loosely embracing said standard to grip and move and then release it by steps, said bar being controlled to cause said lug to end-engage and fractionally brake the standard to hold the latter at times when it is released by said jaws, and said 70 lug being adapted to be released from the standard when the latter has passed from its path to permit the resilient control of the bar to propel it across the adjacent end of the standard in 75 unlocking the bar.

2. In a mechanism of the character described, a resiliently controlled reciprocatory bar having a side lug, a reciprocatory standard, resiliently controlled, mounted alongside said bar to cross the path of the lug in a direction at a right angle to the bar, a rock-arm, resiliently controlled, having relatively staggered jaws loosely embracing said standard to grip and move and then release it by steps, means for adjustably limiting the scope of swinging movement of the rock-arm, the resilient control of said bar causing said lug to frictionally end-engage the standard to hold the latter at times when it is released by said jaws, said lug becoming released from the standard when the latter has passed from its path to permit the resilient control of the bar to propel it across the adjacent end of the standard in unlocking the bar, and means for cushioning said bar at the end part of said movement.
3. In a mechanism of the character described, a resiliently controlled reciprocatory bar having a side lug, a reciprocatory resiliently controlled standard mounted alongside said bar to cross the path of the lug in a direction at a right angle to the bar, a resiliently controlled rock-arm having relatively staggered jaws loosely embracing said standard to grip and move and then release it by steps, means for adjustably limiting the scope of swinging movement of the rock-arm, said bar being resiliently controlled to cause said lug to end-engage the standard to hold the latter at times when it is released by said jaws, said lug being adapted to become released from the standard when the latter has passed from its path to permit the resilient control of the bar to propel it across the adjacent end of the standard in unlocking the bar, said bar having therealong a pair of depressions, a counting device having a member ridable upon the bar and into or out of one depression for actuating the device by steps, and a signaling device having an element also ridable upon the bar and into or out of the other depression for actuating the signal device when the bar is unlocked.
4. In a mechanism of the character described, a housing, mechanism therein including in combination a resiliently controlled reciprocatory bar having a side lug, a resiliently controlled standard mounted alongside said bar to cross the path of the lug in a direction at a right angle to the bar, a resiliently controlled rock-arm having relatively staggered jaws loosely embracing said standard to grip and move and then release it by steps, means for rocking said rock-arm, said bar being controlled to cause said lug to end-engage the standard to hold the latter at times when it is released by said jaws, a screw mounted in the rock-arm and fulcrumed on a fixed part of said housing for adjusting the scope of rocking movement of the rock-arm, and said lug being adapted to be released from the standard when the latter has passed from its path to permit the resilient control of the bar to propel it across the adjacent end of the standard in unlocking the bar.
5. In a mechanism of the character described, a resiliently controlled reciprocatory bar having engaging means thereon, a resiliently controlled standard mounted adjacent said bar to cross the path of said engaging means, a resiliently controlled rock-arm having ratcheting means fixed thereon loosely related to said standard to grip and move opposite walls thereof and then release it by steps, means for adjustably limiting the scope of movement of the rock-arm, said bar being controlled to cause said engaging means to engage said standard at times when the standard is released by the ratcheting means, means for rocking said rock-arm, and said engaging means being adapted to be released from the standard when the latter has passed from the path of said means to permit the resilient control of the bar to propel the said means across the adjacent end of the standard in unlocking the bar.
6. In a mechanism of the character described, a resiliently controlled reciprocatory bar having engaging means thereon, a resiliently controlled standard mounted adjacent said bar to cross the path of said engaging means, a rock-arm having ratcheting means thereon loosely related to said standard to grip and move and then release it by steps, said bar being controlled to cause said engaging means to engage said standard at times when the standard is released by the ratcheting means, said engaging means being adapted to become released from the standard when the latter has passed from the path of the engaging means to permit the bar to be propelled to carry the engaging means across the standard, said bar having a depression, and a counting device having an operating member ridable upon the bar and into or out of said depression for actuating the device by steps.
7. In a mechanism of the character described, a resiliently controlled reciprocatory bar having engaging means thereon, a standard mounted for reciprocation adjacent said bar to cross the path of said engaging means, an adjustably fulcrumed rock-arm having ratcheting means thereon loosely related to said standard to grip and move and then release it by steps, said bar being controlled to cause said engaging means to engage said standard at times when the standard is released by the ratcheting means, said engaging means being adapted to become released from the standard when the latter has passed from the path of the engaging means to permit the bar to be propelled to carry the engaging means across the standard, said bar having other engaging means, a signaling device, and an element ridable upon the bar and operable by the engaging means for actuating the signal.
8. In a mechanism of the character described, a resiliently controlled reciprocatory bar having engaging means thereon, a resiliently controlled standard mounted adjacent said bar to cross the path of the engaging means, a rock-arm having ratcheting means thereon loosely related to said standard to grip and move and then release it by steps, a fixed body, a screw rotatably mounted on the free end of the rock-arm to end-engage the fixed body to adjustably limit the swing of the rock-arm, said bar being controlled to cause said engaging means to engage said standard at times when the standard is released by the ratcheting means, said engaging means being adapted to become released from the standard when the latter has passed from the path of the engaging means to permit the bar to be propelled to carry the engaging means across the standard, said bar having in opposite longitudinal edges cam depressions, a signaling device, an element ridable upon the bar and operable by one of said depressions for actuating the signal, and a counting device having an operating member ridable upon the bar and operable by the other of said depressions for actuating the counting device by steps.
9. In a mechanism of the character described,

a resiliently controlled reciprocatory bar having engaging means thereon, an adjustable resiliently controlled standard mounted adjacent said bar to cross the path of said engaging means, a resiliently controlled rock arm having ratcheting means thereon loosely related to said standard to grip and move and then release it by steps, said bar being controlled to cause said engaging means to engage said standard at times when the standard is released by the ratcheting means, said engaging means being adapted to become released from the standard when the latter has passed from the path of the engaging means to permit the bar to be propelled to carry the engaging means across the standard, resiliently controlled pivotally connected elements for rocking said rock-arm, means for adjustably limiting the scope of movement of said standard, and adjustable stop means mounted on the rock-arm to limit the swing of its free end in one direction by engagement with an abutting fixed body.

10. In a mechanism of the character described, a resiliently controlled reciprocatory bar having engaging means thereon, a resiliently controlled standard mounted adjacent said bar to cross the path of the engaging means, a rock-arm, having oppositely toothed ratcheting means thereon loosely related to said standard to grip and move and then release it by steps, said bar being controlled to cause said engaging means to engage said standard at times when the standard is released by the ratcheting means, said engaging means being adapted to become released from the standard when the latter has passed from the path of the engaging means to permit the bar to be propelled to carry the engaging means across the standard, resiliently controlled means for linkedly rocking the rock-arm, means for adjustably limiting the scope of movement of said standard, adjustable stop means mounted on the rock-arm to limit the swing of its free end in one direction by engagement with an abutting fixed body, means for cushioning the reciprocatory bar at one end, and said bar having engaging means, separated from each other, for actuating in the one case an operating member of a counting device, and in another case a concussion element for actuating a signaling device.

11. In a mechanism of the character described, in combination, a sliding lock bar, parts controlled by said lock bar for locking the discharge of a mixing machine, a member normally tending to move the lock bar to a releasing position in respect to its locking function, a latch member operating releasably and rectilinearly to the lock bar to hold the lock bar in locking position, and instrumentalities operable by a mixing machine during its mixing cycle to intermittently actuate the latch member until it reaches a position disengaged from the lock bar in respect to its locking action, whereby the lock bar may move automatically to a released position, said last mentioned instrumentalities including a mixing drum operated rocker lever, a pivoted clutch member coacting with the latch member, and connecting means between the rocker lever and said pivoted clutch member, the pivoted clutch member comprising spaced jaws between which the latch member is received, one of the said jaws having intermittent releasing and clutching cooperation with the latch member.

12. In a mechanism of the character described, in combination, a locking bar for preventing the

discharge action of a mixing machine, means for setting said locking bar in locking position, a latch member coacting with the locking bar to hold it in locking position for a predetermined time, a clutch bar cooperating with the latch member for moving the latter to release the lock bar, an instrumentality normally tending to move the latch member into cooperation with the locking bar, and a device operable by a mixing device to intermittently actuate the clutch bar and thereby transmit movement to the latch member until it reaches its position releasing the locking bar, a signal, and a striker for the signal arranged rectilinearly of the lock bar, the said lock bar having a camming element to operate said striker upon release movement of the lock bar.

13. In a mechanism of the character described, in combination, a locking bar for preventing the discharge action of a mixing machine, means for setting said locking bar in a locking position, a latch member coacting with the locking bar to hold it in locking position for a predetermined time, a clutch bar cooperating with the latch member for moving the latter to release the lock bar, an instrumentality normally tending to move the latch member into cooperation with the locking bar, and a device operable by a mixing device to intermittently actuate the clutch bar and thereby transmit movement to the latch member until it reaches its position releasing the locking bar, a counter, a part for actuating the counter arranged rectilinearly of the lock bar, said lock bar having a camming element to actuate the last mentioned part on release movement of the lock bar.

14. In a timer for a rotary batch mixer, in combination, a resiliently controlled locking bar mounted for limited to and fro movements and having an offset laterally extending lug thereon, a resiliently controlled stop-bar positioned for to and fro displacements across one side of the locking bar in the path of said lug, a resiliently controlled ratcheting arm, swingable, and having a transverse aperture with staggered teeth on opposite walls thereof, said stop-bar loosely traversing said aperture, means for adjusting the scope of swinging movement of said arm, and means for actuating said arm, in ratcheting the stop-bar in one direction by steps, the locking bar having opposite edge depressions for at times 50 coacting with actuating parts of a signaling device and a counting device.

15. In a timer for a rotary batch mixer, in combination, a resiliently controlled locking bar mounted for limited to and fro movement and 55 having an offset laterally extending lug thereon, a resiliently controlled stop-bar positioned for to and fro displacements across one side of the locking bar in the path of said lug, a resiliently controlled ratcheting arm, swingable, and having 60 a transverse aperture with staggered teeth on opposite walls thereof, said stop-bar loosely traversing said aperture, means for adjusting the scope of movement of said arm, means for actuating said arm in ratcheting said stop-bar by 65 steps releasably, and means for adjustably limiting the scope of movement of said stop-bar, consisting of a lug thereon, a fixed threaded standard and a nut mounted on said standard in the path of movement of said lug.
